DISGUISSABLE TOY CAP RIFLE

John W. Ryan, 688 Nimes Road, Bel-Air, Calif.

Filed Apr. 12, 1965, Ser. No. 84,719

Term of patent 14 years

(Cl. D34—15)

Fig-4

Fig-10

Fig-3

Fig-9

Fig-8

FIGURE 1 is a right-hand elevational view of a disguised top cap rifle showing my new design in open position,

FIGURE 2 is an end elevational view taken from the right of FIGURE 1,

FIGURE 3 is a left-hand side elevational view of the design in open position,

FIGURE 4 is an end elevational view taken from the right of FIGURE 3,

FIGURE 5 is a top plan view of the design in open position,

FIGURE 6 is a front elevational view of the design in closed position,

FIGURE 7 is a rear elevational view of the design in closed position,

FIGURE 8 is an end elevational view taken from the right of the design shown in FIGURE 6,

FIGURE 9 is an end elevational view taken from the right of the design shown in FIGURE 7, and

FIGURE 10 is a top plan view of the design in closed position.

I claim:

The ornamental design for a disguised toy cap rifle, as shown.
